UNITED STATES PATENT OFFICE.

WILLIAM D. GRAY, OF MILWAUKEE, WISCONSIN, ASSIGNOR TO E. P. ALLIS & CO., OF SAME PLACE.

GRINDING-MILL.

SPECIFICATION forming part of Letters Patent No. 388,968, dated September 4, 1883.

Application filed July 25, 1884. Serial No. 138,780. (No model.)

To all whom it may concern:

Be it known that I, WILLIAM D. GRAY, of Milwaukee, in the county of Milwaukee and State of Wisconsin, have invented a certain 5 new and useful Improvement in Grinding-Mills, of which the following is a full, clear, and exact specification.

This invention relates to those grinding-mills in which provision is made for throwing 10 the co-operating rolls apart at will to stop the grinding action, and in which the delivery of the material to the grinding-rolls is controlled by an adjustable gate connected by intermediate devices with the roll-spreading mechanism, so that the adjustment of the gate and the 15 rolls is effected at one operation.

As the mills are usually adjusted, the movement of the gate and the rolls is effected simultaneously. My improvements relate to a mechanism 20 whereby the feed-gates are first closed and the grinding-rolls subsequently separated at one operation, the rolls being thus permitted to reduce the material already delivered upon them before they are separated.

25 It also relates to a construction and arrangement of mechanism whereby the opening of the gates is effected previous to the closing of the rolls, so that there will be no danger of the rolls running in contact with each other.

30 My improvement is applicable alike to mills having a single pair of rolls and to those having two pairs of rolls, which are commonly denominated "double-roller mills." I have shown the invention applied to both forms of 35 mill.

As the invention is susceptible of modification in the form of its embodiment, I have also represented in the drawings certain of these changes.

40 In the accompanying drawings, Figure 1 represents a side elevation of a double-roller mill having my improvement incorporated therein, the side of the hopper being broken away to expose the internal feed-gates. Fig. 2 is a side 45 elevation of another double mill having my improvement applied thereto in a form somewhat different from that in the preceding figure. Fig. 3 is a cross-section on the line xx of Fig. 1. Fig. 4 is a side elevation of a "single mill" provided with devices similar to those shown in Fig. 1, a portion of the feed-

roll and hopper being shown in section. Fig. 5 is an elevation, partly in section, showing another form of my mechanism. Fig. 6 is a cross-section on the line yy of Fig. 5. Fig. 7 55 is a sectional view illustrating a modified form of the parts shown in Fig. 6. Fig. 8 is an elevation, partly in section, of one side of the feed-hopper, the feed-roll, the feed-gate, and attendant parts. 60

Referring to Fig. 1, A represents the base or frame of the mill; B B, two grinding-rolls in fixed bearings therein; C C, the grinding-rolls mounted in the upper ends of arms D, which are pivoted at or near the middle to 65 their frame. At their lower ends these arms are connected to rods E, which are extended inward to the middle of the frame and mounted at their inner ends upon and around eccentrics F on a rock-shaft, G, passing through the 70 frame from side to side, the rotation of this shaft serving through the eccentrics, rods, and roll-supporting arms to throw the two movable rolls simultaneously toward or away from the fixed rolls. These parts constitute what is 75 commonly known as the "roll-spreading mechanism," and are not separately claimed herein.

The rock-shaft is provided at one end with a crank-arm, H, pivoted to a pitman, I, which extends upward to one end of an angular hand-lever, J, pivoted on the side of the main frame, the lever serving through the intermediate parts to effect the spreading of the rolls. The pitman, instead of being pivoted to the hand-lever, is slotted at its upper end to receive a 80 stud on the lever, whereby a limited amount of play or lost motion is allowed between the lever and pitman, for a purpose which will presently appear. At its top the mill is provided with the usual feed-hopper, K, having 85 at its lower side two throats, through which the material passes to the respective pairs of grinding-rolls. Beneath each throat is a horizontal feed-roll, L, which may receive motion in any ordinary or suitable manner, the present invention having no relation thereto. 90

Over each feed-roll I mount a vertically swinging or revolving gate, S, in the form of a segment of a hollow cylinder, provided at the ends with ears, through each of which a 95 pivoted bolt or pin, a, is extended. The outer surface of the gate is concentric with the pivot 100

and is fitted closely against the inner surface of the hopper to maintain a tight joint and prevent the escape of material, except as it may pass between the lower edge of the gate 5 and the upper surface of the feed roll. Each gate is provided with an upright arm, *b*. The arms of the two gates are connected by rods *c* to opposite ends of a cross-bar or double crank, *d*, located at the side and upon the journal or 10 pivot of the hand-lever *J*.

Between the hand lever and the cross bar or lever *d* is a frictional plate or washer, *f*, which transmits motion from the hand-lever to the cross-bar and gates, at the same time permitting 15 the lever to continue its movement in either direction after the motion of the gates and their connection is arrested. The upward opening movement of each gate is limited by a stoppin, *g*, applied to the hopper, as in Fig. 4, 20 while their downward movement is limited by their contact with the feed-rolls or otherwise, as may be desired.

The operation of the parts is as follows: Assume that the parts stand in the position 25 shown in Fig. 1, with the grinding-rolls separated and the feed gates closed. At this time the stud on the hand-lever will stand in the lower end of the slot of the roll-controlling pitman *I*. On moving the hand-lever to the 30 right, motion is communicated therefrom through the frictional plate or washer to the lever *d*, and thence to the two feed-gates, which are caused to open. At or about the instant that the feed-gates reach their limit of movement 35 the stud on the hand-lever encounters the upper end of the slot in the pitman *I*, whereupon, the motion of the lever being continued, the pitman is elevated and caused through the intermediate connections to close 40 the grinding-rolls. Thus it will be seen that the movement of the hand-lever to the right first causes the opening of the feed-gates and afterward closes the rolls to a position for grinding. If with the parts in a grinding position 45 the hand-lever is moved to the left, it will first have the effect of closing the feed-gates, and thereafter, its stud having in the meantime reached the lower end of the slot, it will cause the grinding-rolls to separate. 50 The foregoing operation of the parts is in practice of the highest importance, since it prevents the grinding-rolls from being opened at such time as to permit the passage of the unground material accumulated on them, and, 55 on the other hand, prevent the rolls from being brought together except at the instant the material is delivered to them. Consequently the mill is free from liability to permit the passage of unground material, and also free 60 from liability of the rolls acting injuriously upon each other.

Referring to the mill represented in Fig. 2, A represents the frame; B, the stationary rolls; C, the movable rolls, and D upright arms in 65 which the movable rolls are mounted. These arms are pivoted at the lower end and the two arms which sustain each roll connected by rods

E to eccentrics F and a transverse rock-shaft, G, there being one of these shafts for each movable roll. The rock-shafts are provided with crank- 70 arms H and connected by a cross-bar, O, engaging studs on the arms. This bar is slotted for the passage of the studs, so that it may play endwise to a limited extent without imparting motion to the arm or roll spreading 75 devices. The double hopper K on the top of the machine is provided with vertically-sliding feed-controlling gates of ordinary form, and two horizontal feed-rolls are arranged below the gates and above the grinding-rolls, 80 as usual. Each gate is operated by a rock-shaft, P, mounted within the hopper and provided with a projection which engages between studs or shoulders on the gate. The rock-shafts P are provided with depending arms m, connected by rods n to a cross-bar or double crank, d, mounted centrally on a stud, e, on the frame or hopper. The parts thus arranged cause 85 the two gates to open or close simultaneously.

By the side of the lever *d*, and on the same 90 journal therewith, is an arm, *p*, the lower end of which bears between two studs, *q*, on the side of the roll-spreading bar O. The arm *p* has a frictional connection with the lever *d*, the two parts being arranged to bear directly 95 against each other or against an intervening washer of elastic material. This washer may be applied in a flat form, as shown in Fig. 7; or, if it be omitted, the two parts *o* and *r* of the parts *d* and *J* may be made concave and convex, as shown in Fig. 6, to produce the required degree of friction between them. 100

Assuming the parts to stand in the position shown in Fig. 2, with the feed-gates open and the grinding-rolls closed, the movement of the bar O to the left will first have the effect of operating the arm *p*, and through the intermediate parts of closing the feed-gates. During the closing action of the gates the arms H are permitted to remain at rest by reason of 105 the slotted connection between them and the arm O; but at or about the time that the closing action of the gates is completed the ends of the slots in the bar strike the studs on the crank-arms H, thereby separating the rolls. 110 A reverse movement of the bar O—that is, a movement to the right—will have the effect of 115 first opening the gates and subsequently closing the rolls.

In Fig. 4 I have represented a mill containing a single pair of grinding-rolls with a rotary feed-gate connecting two roll-spreading devices in form and arrangement identical with those represented in Fig. 1, the same letters indicating like parts in the two figures, 120 and the parts shown in Fig. 4 operating in the same manner and with the same effect as the corresponding parts in the first figure.

It is to be noted that my improvements may be applied in connection with gates and gate-adjusting devices of any approved form. 125

In Fig. 8 I have illustrated a sliding gate provided with a rack and operated by a pinion or rock-shaft. This construction may be

substituted in place of that represented in the previous figures.

I am aware that mechanism for adjusting a grinding-roll has been combined through intermediate devices with a mechanism for adjusting a feed-gate, the spreading of the rolls occurring simultaneously with the closing of the gate, and vice versa, and to such construction I lay no claim.

10 I do not claim herein the combination of a roll-spreading mechanism and a feed-roll-driving mechanism to cause the stoppage of the feeding and grinding actions successively, the same being described and claimed in my application for Letters Patent No. 135,793, filed June 23, 1884; nor do I claim herein the specific form of gate-controlling and roll-spreading mechanism shown in my application for patent, No. 138,781, filed July 25, 1884.

15 20 It will be observed that in each embodiment of my invention, as herein represented, the roll-spreading and the gate-operating mechanisms are connected by a motion-retarding device—that is to say, a device which causes 25 said mechanisms to operate successively instead of simultaneously.

Having thus described my invention, what I claim is—

1. In a grinding-mill, the combination of a 30 hopper, a feed-controlling gate, two grinding-rolls, one of which is movable, roll and gate adjusting mechanisms, an operating-lever, a device permitting a loose sliding connection with the roll adjusting mechanism, and a friction-coupling with a gate-adjusting mechanism.

35 2. In a grinding-mill, the combination of

the grinding-rolls, a roll-spreading mechanism, and a hand-lever to operate the spreading mechanism, with a feed-controlling gate, a stop 40 to limit the motion of the gate, gate-operating mechanism, and a frictional connection between the gate-operating mechanism and the lever.

3. In a roller grinding-mill, the combination of a hopper, a feed-controlling gate and its operating mechanism, a stationary grinding-roll, B, a movable grinding-roll, C, a bar, I, intermediate devices between said bar and the movable roll, the hand-lever J, connected 50 to the bar I and having a limited movement independent thereof, and a friction-coupling connecting the feed-controlling gate and the gate operating devices with lever J, substantially as described.

4. In a roller grinding-mill, the combination of the grinding-rolls, a roll-spreading mechanism, as usual, a feed controlling gate, and gate-operating mechanism, as usual, and an intermediate motion-retarding device connecting said mechanisms, as described, in such relation that they are caused to operate successively instead of simultaneously.

5. In a roller grinding-mill, the combination of the roll-spreading mechanism, a feed- 65 controlling gate and its operating mechanism, and a motion-retarding device connecting said mechanisms in position to cause the closing of the gate and spreading of the rolls in the order named.

WILLIAM D. GRAY.
